UNITED STATES PATENT OFFICE.

JOSHUA ILLINGWORTH AND AMOS M. BAKER, OF CLEVELAND, OHIO.

BRAKE MECHANISM FOR ELECTRIC STREET-CARS.

SPECIFICATION forming part of Letters Patent No. 434,063, dated August 12, 1890.

Application filed May 5, 1890. Serial No. 350,699. (No model.)

To all whom it may concern:

Be it known that we, JOSHUA ILLINGWORTH and AMOS M. BAKER, of Cleveland, in the county of Cuyahoga and State of Ohio, have 5 invented certain new and useful Improvements in Brake Mechanism for Electric Street-Cars; and we do hereby declare the following to be a full, clear, and exact description of the invention, such as will enable others 10 skilled in the art to which it pertains to make and use the same.

Our invention relates to improvements in brake mechanism for electric street-cars in which the momentum of the armature is utilized in setting the brakes whereby the car is retarded by the action of the brake-shoes on the car-wheel, so that little or no strain is sustained by the gearing that connects the armature-shaft with the car-axle.

20 In the accompanying drawings, Figure 1 is an elevation, partly in section, of an armature, friction-clutch, and mechanism for operating the clutch. Fig. 2 is a side elevation showing more especially the running-gear of the car. Fig. 3 is a plan in diagram. Figs. 25 4, 5, and 6 are enlarged views in detail, Figs. 4 and 5 being elevations, the former partly in section, and Fig. 6 being a plan.

A represents the body of the car; B, the 30 car-wheels; C, the armature, and C' the armature-shaft. To the one end of the armature-shaft, preferably the end opposite the gears, is rigidly attached the male member C² of a friction-clutch. This member overhangs the 35 shaft and has an internal flange c at the outer extreme thereof, this flange being separated, say an inch, (more or less,) from the end of the armature-shaft.

D is a short shaft or round bar that fits 40 easily inside of flange c, this shaft having a head D' located between flange c and the end of the armature-shaft. The one journal-bearing for the armature-shaft is supposed to be at c', and the outer end of shaft D is supposed 45 to be supported by a bracket-arm or any suitable device connected with the frame-work, whatever it may be, that supports the armature, and as shaft D does not revolve on its axis the only requisite in supporting this 50 shaft is that it be kept in line with the armature-shaft.

On shaft D is mounted with an easy fit

the female member d of the clutch, the periphery of member d being provided with sprocket-teeth d' for engaging an endless 55 chain f. The outer face of member d is recessed at d² for receiving with an easy fit heads E' of sleeve E, member d being provided with a cap d³, that fits outside of head E', these parts fitting loosely, so that member 60 d may turn without turning the sleeve. Sleeve E has an easy fit on shaft D for the purpose of moving this sleeve endwise on the shaft. This shaft has a long mortise or slot D² in which operates a link G. The link has a diagonal slot g, adapted to straddle pin or bolt D³ of shaft D. Sleeve E is slotted at e to receive link G with an easy fit.

H is a rock-shaft extending lengthwise of the car and suspended from the car-body by 70 suitable brackets, the shaft being provided at the extremes thereof with hand-levers H' for operating the same, these hand-levers being located preferably next beside the dashboards a a. Shaft H has a laterally-projecting rock-arm h, that is pivoted to link G, so that by moving levers H' laterally link G is depressed or elevated to open or close the friction-clutch. With the construction shown, and by reason of bolt or pin D³ operating in 75 the inclined or diagonal slot g, it is evident that when the link is depressed it will crowd the sleeve toward the armature and thus close the clutch, and that the reverse will occur when the link is elevated.

I is a lateral shaft supported by suitable 80 journal-boxes depending from the car, this shaft bearing a sprocket-wheel I', that is engaged by endless chain f aforesaid. This shaft is provided with a small drum i, on 90 which may be wound in either direction chain i', the latter connecting with the brake-lever J.

The brake mechanism is substantially as heretofore used, comprising, in the main, 95 brake-beams K, provided with brake-shoes k, the brake-beams being supported by the link and provided with springs for backing off the brake-shoes, all of which are so well known that it is not considered necessary further to illustrate or describe them. Lever J is pivoted at J', and rods j j connect this lever with the brake-beams in the manner shown in the diagram. By operating lever H' the friction-clutch is opened or closed. When the clutch 100

is closed, whereby shaft I is set in motion to wind up chain i' for setting the brakes, the momentum of the armature is utilized in setting the brakes, and the brakes in turn stop 5 the car, by which arrangement there is little or no strain or wear on the gearing that connects the armature-shaft with the car-axle.

Heretofore where brakes have been set by hand or have been operated by mechanism 10 connected with one of the car-axles the momentum of the armature had to be overcome by the gearing, thus causing backlash and much noise and wear, all of which is overcome by our improved construction.

15 With the construction shown it is evident that there is no end strain on the armature-shaft in opening and closing the clutch, for the reason that the pressure applied to sleeve E is sustained by the shaft D and the latter 20 being coupled with the armature-shaft.

What we claim is—

1. The combination, with brake mechanism, of an armature and means by which the momentum of the latter may be utilized to operate the brake mechanism, substantially as 25 set forth.

2. In brake mechanism for electric street-cars, in combination, an armature, the shaft thereof bearing the one member of a friction-30 clutch, the opposing member of the clutch being operatively connected with the brake mechanism of the car, suitable means, preferably as shown, being provided for opening and closing the clutch, substantially as set forth.

3. The combination, with armature-shaft 35 bearing the one member of a friction-clutch, of a stationary shaft coupled to the armature-shaft and bearing the other member of the clutch, a sleeve for operating the latter, such sleeve being mounted on the stationary shaft, 40 means for shifting the sleeve in opening and closing the clutch, and the loose member of the clutch being operatively connected with the brake mechanism of the car, substantially as set forth.

4. The combination of armature-shaft coupled with the stationary shaft, the former bearing the one member of a friction-clutch and the latter bearing the other member of the clutch and bearing a sleeve for operating the latter, 50 the shaft and sleeve being slotted to receive a link, and the link having a diagonal slot fitting astride the pin of the shaft, means for raising and lowering the link for shifting the sleeve endwise, substantially as set forth.

5. The combination, with an armature for propelling a street-car, of a clutch or brake mechanism for retarding the momentum of the armature, substantially as set forth.

In testimony whereof we sign this specification, in the presence of two witnesses, this 2d day of May, 1890.

JOSHUA ILLINGWORTH.
AMOS M. BAKER.
